UNITED STATES PATENT OFFICE.

WILLIAM R. KEACHIE, OF ST. MARY'S, CANADA.

IMPROVEMENT IN CAR-COUPINGS.

Specification forming part of Letters Patent No. 177,722, dated May 23, 1876; application filed December 31, 1875.

To all whom it may concern:

Be it known that I, WILLIAM ROBERTSON KEACHIE, of St. Mary's, in the Province of Ontario and Dominion of Canada, have invented certain new and useful Improvements in Car-Couplings; and I do hereby declare that the following is a full, clear, and exact description thereof, which will enable others skilled in the art to which it appertains to make and use the same, reference being had to the accompanying drawings, and to the letters of reference marked thereon, which form a part of this specification, and in which—

Figure 1 is a front elevation. Fig. 2 is a longitudinal vertical section. Fig. 3 is a top plan, and Fig. 4 is a side elevation.

Similar letters of reference indicate corresponding parts in all the figures.

The object of my invention is to provide a car-coupling that combines certainty of action with great strength; and it consists in the construction and combination of its working parts, hereinafter more fully shown and described.

In the drawing, A is the draw-head, in the top of which is a longitudinal slot, a. In this slot is pivoted, by means of a pin, b, the hammer-catch or hook B, of the configuration shown in the drawing—that is, consisting of a shank having a downwardly-projecting, inwardly-slanting pin, c, and head C, which abuts upon the outer rim d of the draw-head. The hammer B is operated by a latch or tongue, E, pivoted under it, in the recess of the draw-head, by means of a pin, e, upon which it is firmly affixed. Pin e extends to the outside of the draw-head, where it has a lever, G, by means of which it and the latch E may be turned, so as to raise hammer B for uncoupling.

Affixed rigidly upon the inside walls of recess D are two blocks, (denoted by F,) beveled in front, so as to slant upwardly toward the upper rim d of the draw-head A. These blocks are of such a thickness or width as to form a narrow opening in the middle of recess D, only sufficiently wide to allow of the insertion from the top of the hammer-catch B, which, in its locked position, (shown in the drawing,) will be prevented from moving laterally by the blocks F abutting against its sides. These

blocks also serve, by their slanting fronts or faces, to guide the link, when inserted, against the beveled pin or hook c of the catch B, by which the coupling is effected.

In the bottom of recess D is a mortise, i, into which pin c of hammer B enters, thus preventing the possibility of uncoupling by accident.

The advantages of my improved car-coupling will be easily perceived from the foregoing description. Its construction being exceedingly simple, it can be manufactured at a small cost. The configuration of pin c of hammer B insures certainty of action when coupled, and the weight of hammer B makes uncoupling by accident simply impossible, while, whenever desired, it is easily uncoupled by simply raising lever G, which may be connected by rods or chains with the top or side of the car. It will also be observed that when the cars are in motion the strain does not all come upon pivoting-pin b, but is divided between it and the rim d of the draw-head, upon which head C of hammer B abuts. This increases the strength of this coupling greatly.

The blocks F will, in turning curves, bear against the sides of the hook B C, relieving the strain from off the draw-head and pin b; these blocks or shoulders, besides, greatly strengthening that part of the draw-head that has to stand the greatest strain and wear in coupling, uncoupling, or pulling the cars. Fitting close against the sides of hook B C, they also prevent rattling or jarring of the hook when the train is in motion.

Having thus described my invention, I claim and desire to secure by Letters Patent of the United States—

The slotted draw-head A, having inclined blocks or shoulders F rigidly affixed to its sides, in combination with a closely-fitting coupling-hook, B C, all constructed substantially as described, and for the purpose specified.

In testimony that I claim the foregoing as my own I have hereto affixed my signature in presence of two witnesses.

WILLIAM ROBERTSON KEACHIE.

Witnesses:

LOUIS BAGGER,
WM. BAGGER.
